(57) **CLAIM**

The ornamental design for an airway intubation kit, as shown and described.

DESCRIPTION

FIG. 1 is a top perspective view of an airway intubation kit, according to the present invention.

FIG. 2 is a front view thereof. The back view is a mirror image of the front view.

FIG. 3 is a left view thereof. The right view is a mirror image of the left view.

FIG. 4 is a top view thereof.

FIG. 5 is a bottom view thereof.

FIG. 6 is a bottom perspective view thereof; and,

FIG. 7 is a top perspective view thereof.

The broken lines in the drawings depict environmental subject matter and form no part of the claimed design.
